BY

Robert A. Sloman.
ATTORNEY

manual rotation of shaft 22 in one direction or the other will cause either inward or outward longitudinal movements of platforms 16 and 17 with respect to each other upon the top surface of swivel 13.

A pair of longitudinal spaced guide rails 29 positioned upon the top surface of swivel 13 and secured thereto as by nails 30, are arranged parallel to each other and to slot 15 as well as to platform elements 16 and 17.

Upwardly extending stops 31 are arranged upon the opposite ends of guide bars 29 and are adapted for respective engagement with cross-bars 32 and 33 secured respectively to platform elements 16 and 17 to limit outward adjustment thereof.

As shown in Figure 4 a pair of upright rudder shaped elements 34 are arranged and secured to the outer ends of platforms 16 and 17 being transversely notched at 35 to receive cross-bars 32 and 33 respectively which move with platforms 16 and 17 and which cooperatively bear upon the top surfaces of guide bars 29.

As viewed in Figure 2, hollow U-shaped element 36 is suitably secured to platform 16 for longitudinal adjustment therewith, being slotted at 37 to receive outwardly extending guide bars 29.

A corresponding U-shaped element 38 is oppositely arranged from U-shaped element 36, being secured to platform 17 for longitudinal adjustment therewith; there also being slots 39 formed therein to receive guide bars 29 relatively to which element 38 is movable in unison with platform 17 to which it is attached.

The free ends of elements 38 slidably project within the free ends of element 36 in a telescoping action whereby in any of the adjusted positions of platforms 16 and 17 said U-shaped elements 36 and 38 ornamenteally form the side walls of a boat, for instance.

A pair of upright transversely arranged book end elements or stops 40 are respectively mounted upon platforms 16 and 17 with their lower bifurcated ends 41 slidably extending down through the corresponding transverse openings in platforms 16 and 17.

Rollers 42 are mounted upon the lower ends of the bifurcated portions 41 and are adapted to cooperatively engage the same surface upon which base 14 is mounted to facilitate rotary movement

of said platforms and at the same time provide a secondary support for the outer ends thereof.

Detent means 43 are pivotally mounted upon the lower portions of bifurcated elements 41 within central slots 44 to normally prevent the upward removal of bifurcations 41, but which may be manually tilted inwardly within slots 44 whereby said bifurcated element 40 may be removed from the respective platforms if desired.

Having described my invention, reference should now be had to the claim which follows for determining the scope thereof.

I claim:

15 In combination, a base, a pair of co-planar platform elements slidably mounted upon said base in horizontal position, a pair of spaced longitudinally extending guide rails positioned above said platform elements and joined to said base in substantially parallel relation to said platform elements, upwardly extending stops upon the outer ends of said rails, and transverse bars carried by said platform elements, being positioned for cooperative sliding engagement with the top surfaces of said rails, the outward adjustment of said platform elements being limited by said bars engaging said stops.
